UNITED STATES PATENT OFFICE.

ALFRED HILEY, OF RICKMANSWORTH, ENGLAND, ASSIGNOR TO THE BRITISH STEEL
PILING COMPANY, LIMITED, OF WESTMINSTER, ENGLAND, A BRITISH COMPANY.

CONSTRUCTION OF CONCRETE PILES.

Application filed November 14, 1927, Serial No. 233,239, and in Great Britain October 29, 1926.

This invention relates to the construction of concrete piles in accordance with the method forming the subject of prior British Patent No. 197,430 in which the concrete is deposited from a tube and tamped and consolidated within a hole in the ground by vertical vibratory movements given to the tube by an upwardly and downwardly striking hammer, the pile being built up by a succession of operations each of which involves the depositing of a portion of the concrete from the tube by an upward movement of the latter occasioned by the upward blow of the hammer which frees the concrete so that it falls down the tube by gravity, and the tamping of the deposited concrete by a downward movement of the tube under the combined influence of gravity and the force exerted by the downward pressure or blows of the hammer. Under this method as described in the specification of the said patent the length of the pile is determined by the length of the tube and as the latter cannot, for practical reasons, conveniently be made of greater length than about fifty-five feet, this represents approximately the maximum length of a pile that can be made by the said method without joining on additional lengths of tubes which is disadvantageous. It occasionally happens, however, that a sufficiently firm stratum of ground for the support of the pile has not been reached at the depth corresponding to the said maximum length of pile and the chief object of the present invention is to provide for the construction of a pile which is not limited by the length of the tube.

According to the invention a pilot pile is driven into the ground by the aforesaid tube under the influence of downward blows of the hammer, until a sufficiently firm stratum is reached, whereupon concrete in a plastic condition is poured into the tube and is deposited and tamped in the hole on top of the pilot pile by vibratory movements of the tube under the influence of upward and downward blows of the hammer. The said pilot pile may be "pre-cast", that is to say cast in any suitable manner and brought to the scene of operations for being driven into the ground, but it is preferably constructed in the ground by the vertical vibratory movements given to the concrete-containing tube as aforesaid and when the pilot pile becomes sufficiently hard (which with rapidly hardening cement will occur in two or three days) the tube is again brought into operation to drive the pilot pile and complete the pile by forming a second or main pile above it in the manner hereinbefore described. If a sufficiently firm stratum has not been encountered by the time the pilot pile has been driven into the ground by an amount corresponding to the full length of the tube, the compound pile (i. e. the combined pilot pile and the second or main pile) are driven into the ground by the tube and a third pile is formed in the manner above described above the second pile. Thus with a tube thirty-three feet long with a piling frame about fifty feet high, a compound pile of about sixty feet in length can be made in two separate operations and one of about ninety feet in length can be made in three separate operations. The hammer may be controlled as described in the specification of the aforesaid patent so that it can at will be used for driving the tube or for giving vibratory movements to the tube whilst forming the piles.

In order to enable the concrete at the top of the pilot pile (whether it be "pre-cast" or constructed in situ) to safely withstand the driving force of the tube the top may be fitted with a metal rim of adequate area and strength and below this a steel casing may be placed and filled with concrete. The said casing is a permanent one and is for maintaining the compressional strength of the concrete which has to take large driving stresses near the top of the pilot pile. The said rim is placed in position after the pilot pile has been formed and the steel casing is filled with concrete by hand. A concrete extension or head of smaller diameter than the pilot pile is formed above the level of the rim by means of a detachable mould casing and to the outer surface of this head there may be attached blocks of wood or other material capable of bearing inside the tube and suitably spaced apart to form directional guides within the tube during the driving of the pilot pile into the ground, thereby preventing the pilot pile from deviating from a straight course as it is forced into the ground. The spaces between the blocks provide for the passage of the concrete during the formation of the second pile above the pilot pile.

In order that the said invention may be

clearly understood and readily carried into effect, the same will now be described more fully with reference to the accompanying drawings, in which:—

5 Figure 1 is a section shewing the pilot pile after it has been constructed in situ,

Figure 2 is a section shewing the pilot pile driven to the required depth in the ground,

10 Figure 3 is a section shewing the second pile constructed above the pilot pile.

Figure 4 is an enlarged view of Figure 1 shewing the pilot pile driven a short distance below the surface of the ground,

15 Figure 5 is a section taken approximately on the line 5, 5 of Figure 4,

Figure 6 is a section taken on the line 6, 6 of Figure 4,

20 Figure 7 is a side elevation of the mould casing for forming the extension or head of the pilot pile, and

Figure 8 is a plan of Figure 7.

A is the pilot pile which in the example shewn in the drawings and about to be described is constructed in situ by vertical vibratory movements given to a concrete-containing tube B by an upwardly and downwardly striking hammer in the manner described in the specification of the aforesaid Patent No. 197,430. The top of the

25 pilot pile finishes a short distance (2 feet for example) beneath the general surface of the ground which is scooped out as shewn in Figure 1. This is to enable the aforesaid

30 rim and casings to be placed in position as will be described. The pilot pile is reinforced with suitable reinforcing members and the longitudinal members are carried a substantial distance above the top of the pile

35 as shewn to form a strong bond with the second or main pile when the latter is formed on top of the pilot pile. When the concrete of the pilot pile has set sufficiently a mild steel casing or band C is placed in position

40 at the top and is filled by hand with plastic concrete. A cast iron or steel driving rim D is then placed in position within the top portion of the casing or band C. A two part mould casing E held together by hoops

45 E¹ (see Figure 7) is then placed in position resting on the rim D. This casing E, which is of smaller diameter than the pilot pile and preferably tapering as shewn, is filled with plastic concrete by hand and is formed

50 with holes E⁴ for the reception of metal cross-rods E². When the concrete in the mould casing E has sufficiently set, the said casing is removed, leaving the cross rods in position in the head or extension A^x of

55 the pilot pile A thus formed. Blocks of wood E³ (four in number for example) are then attached to the head or extension by means of the rods E² and the completed pilot pile is then left to set sufficiently to

60 withstand being driven into the ground

which, with rapidly hardening cement, will occur in two or three days. The said blocks E³ are of such size as to fit fairly loosely within the tube B. After the completed pilot pile has sufficiently set, the tube B is brought into operation to drive the pilot pile before it until a sufficiently firm stratum has been reached, a coil D^x of several turns of hemp yarn being placed between the lower part of the tube B and the driving rim D so as to ensure water tightness between these parts. During the time that the pilot pile is being driven the blocks E³ form directional guides which prevent the pilot pile from deviating from a straight course. This condition is represented in Figure 2. Concrete in a plastic condition is then poured into the tube B and is deposited and tamped in the hole on top of the pilot pile by vibratory movements of the tube under the influence of upward and downward blows of the hammer as aforesaid, the spaces between the blocks E³ providing for the passage of the concrete. The second or main pile thus constructed is represented at F in Figure 90

95 3. The said pilot pile has at its lower end a metal shoe A¹ which was at the lower end of the tube B when the latter was driven into the ground preparatory to forming the pilot pile.

When a "pre-cast" pilot pile is employed

it is provided with the casing or band C,

the driving rim D, the head or extension

A^x and the blocks E³ as above described be-

fore it is driven into the ground.

If a sufficiently firm stratum has not been reached by the time the pilot pile A has been driven into the ground by an amount corresponding to the full length of the tube B, the compound pile composed of the pilot pile A and the second or main pile F are driven into the ground by the tube and a third pile is formed in the manner above described on top of the pile F; in this case the head of the pile F would be constructed in a similar manner to that above described in connection with the pilot pile A.

The determination of when a sufficiently firm stratum has been reached can readily be effected by ascertaining the extent to which

115 the pilot pile moves downwards at each blow of the hammer and this renders it possible to determine the bearing capacity of the pile without its being necessary actually to load the head of the pile as is customary;

120 whereupon the pile can, at will, be either left or lengthened as the case requires.

In cases where the ground is of a very soft nature the concrete for the pilot pile may be deposited in the manner above described

125 within a surrounding casing which is placed in the ground so that it encompasses the concrete depositing tube B which can be withdrawn freely within it, and this prevents the concrete from departing materially.

from its straight shape. Again, when the upper stratum is of a very soft nature, or is actually liquid, as in a river or harbour, the shoe then used would be of suitable length and may extend from the rim D on which the tube bears above ground, to the pointed end so as to reach a bed which is capable of holding up the weight of the parts concerned before the hammer for driving the shoe is brought into action. This extended shoe may be filled with concrete prior to its being placed in position.

What I claim and desire to secure by Letters Patent of the United States is:—

15 1. A method of constructing concrete piles which comprises depositing a mass of plastic concrete in a hole in the ground, allowing said concrete to set to form a pilot pile, driving said pilot pile into the ground until 20 a sufficiently firm stratum is reached and then filling the hole formed by the pilot pile with plastic concrete and allowing it to set.

20 2. A method of constructing concrete piles which comprises forming a hole in the

ground, depositing plastic concrete in said 25 hole through a tube, tamping said plastic concrete by vertical vibratory movements given by upward and downward strokes of a hammer to said tube as it is being withdrawn, allowing the concrete to set to form 30 a pilot pile, driving said pilot pile to the required depth in the ground by means of an empty tube, pouring concrete in a plastic condition into the tube, and depositing and tamping the concrete in the hole above the 35 pilot tube by vibratory movements given to the tube by upward and downward movements of a hammer.

3. A concrete pilot pile having a reduced portion at the upper end thereof over which 40 a driving tube for said pilot pile is adapted to pass, transversely extending rods embedded in said reduced portion with their ends projecting beyond the sides thereof, and blocks secured to the projecting portions 45 of said rods for guiding the driving tube.

ALFRED HILEY.
